UNITED STATES PATENT OFFICE.

JOSEPH SCHWEGLER, OF BUFFALO, NEW YORK, ASSIGNOR OF ONE-HALF
TO ISIDOR SCHWEGLER, OF SAME PLACE.

WRENCH.

SPECIFICATION forming part of Letters Patent No. 258,137, dated May 16, 1882.

Application filed March 28, 1882. (No model.)

To all whom it may concern:

Be it known that I, JOSEPH SCHWEGLER, of the city of Buffalo, in the county of Erie and State of New York, have invented a new and useful Improvement in Wrenches, of which the following is a specification.

The object of this invention is the construction of a wrench which can be quickly adjusted, and which is simple and durable in construction.

My invention consists of the peculiar construction of the wrench, which will be hereinafter fully described.

In the accompanying drawings, Figure 1 is a side elevation of a wrench provided with my improvement. Fig. 2 is a vertical section thereof. Fig. 3 is an end elevation of the head of the wrench. Fig. 4 is a side elevation, representing a modified construction of the head of the wrench.

Like letters of reference refer to like parts in the several figures.

A represents the handle of the wrench, and B a screw-bolt secured to the handle and provided with a right-hand screw-thread, b, and a left-hand screw-thread, c. The bolt B is secured to the handle A by a tang, d, extending through the handle and secured at its opposite end by a screw-nut, E, or any other suitable means. A portion of the tang d is made square or angular, so that the bolt B turns with the handle A.

F represents the upper jaw, provided with a screw-threaded opening, in which the right-hand screw b works, and G represents the lower jaw, having a screw-threaded opening, in which the left-hand screw c works.

h h are guide pins or rods, which are secured to the upper jaw and pass through openings i in the lower jaws, whereby the jaws are retained in a parallel position, but permitted to move toward and from each other in the direction of the guide-rods h. The contiguous faces of the jaws are preferably recessed on one side of the screw-bolt B, as shown at k, whereby the openings between the jaws on opposite sides of the screw-bolts, when the jaws are opened, are made of different size, thereby

enabling the jaws to grasp screw-nuts of two different sizes without changing the position of the jaws; or, if preferred, one of the grasping jaws may be arranged on one side of the screw-bolt only, and one of the jaws may be provided on the opposite side of the screw-bolt with a head, l, as represented in Fig. 4, which enables the device to be used for a hammer. Upon holding the jaws with one hand to prevent them from turning, and turning the handle, with the screw-bolt attached thereto, with the other hand, both jaws are caused to travel toward or from each other on their respective portions of the screw-bolt, according to the direction in which the screw-bolt is turned. In this manner the jaws are quickly adjusted. The length of the right and left hand screw-threads b c is such that both jaws reach the ends of the respective screws on which they work simultaneously, whereby the separating movement of the jaws is arrested by the lower jaw coming in contact with the end of the handle, thereby preventing the upper jaw from moving farther and becoming detached from the screw-bolt.

I claim as my invention—

1. The combination, with the handle A and the right and left hand screw B, secured thereto, of the jaws F G, provided with screw-threaded openings, through which the right and left hand portions b and c of the screw B work, and means whereby both jaws are retained parallel with each other, but permitted to move simultaneously toward and from each other, substantially as set forth.

2. The combination, with the handle A and right and left hand screw B, secured thereto, of the jaws F G, provided with screw-threaded openings, through which the right and left hand portions b and c of the screw B work, and guide-rods h, secured to one of the jaws F and passing through openings in the other jaw, substantially as set forth.

JOSEPH SCHWEGLER.
